(57) **CLAIM**

The ornamental design for a robotic interface, as shown and described.

DESCRIPTION

FIG. 1 is a perspective view of an embodiment of a robotic interface;

FIG. 2 is a first end view of the robotic interface of FIG. 1; FIG. 3 is a top view of the robotic interface of FIG. 1; FIG. 4 is a second end view of the robotic interface of FIG. 1; and,

FIG. 5 is a top perspective view of the robotic interface of FIG. 1.

In the drawings, the broken lines are for the purpose of illustrating portions of the robotic interface that forms no part of the claimed design.
